UNITED STATES PATENT OFFICE.

EMMERICH A. WERNER, OF NEW YORK, N. Y.

BRIDGE.

SPECIFICATION forming part of Letters Patent No. 311,624, dated February 3, 1885.

Application filed April 27, 1882. (No model.)

To all whom it may concern:

Be it known that I, EMMERICH A. WERNER, of the city, county, and State of New York, have invented certain new and useful Improvements in Bridges, of which the following is a full, clear, and exact description.

The object of my invention is to provide a new and improved girder by introducing a plain tension or compression chord with bow-ro girders.

Figures 1 and 2 are side views of different forms of my improved bridge. Fig. 3 is a detail side view of the lower part of one of the bows of my improved girder. Fig. 4 is a cross-sectional view of the same. Fig. 5 is a plan view of the same.

In bow-girders with joints at the top or crown and at the abutments a thrust is exerted against the abutments, and it is well-known that the chords of such bow-girders take up the horizontal thrust of the bow and the action of the bending forces or moments, whatever may be the manner of loading or the kind of bracing used in the girder. It is known that with moving loads the absolute value of the moments is, according to the position of the loads, alternately positive and negative; hence producing alternately tension and compression strains in the chords, so that in an ordinary bow-girder both chords must be constructed and adapted to resist compression as well as tension. The thrust of the bow is always a compression strain. I take this thrust out of the chords by certain members introduced in the bow-girder. The action of the thrust is thus eliminated from the chords, and now it remains to overcome the alternate positive and negative strains in the chords. As is known, the bending forces or moments acting in the chords are represented by the vertical reaction of the abutment and the vertical action of the load, less the bending generated by the action of the horizontal thrust of the bow. It is evident that as long as the latter is less than the former the total action of the bending moments will be positive; hence I calculate the height of the bow at each point in such a manner that the action or bending moments of the horizontal thrust will always be smaller than the action of the moment of the vertical forces—the vertical reaction and loads.

In calculating the height of the bow at each point in such a manner as to have the bending moment arising from the horizontal thrust less than the moment of the vertical forces, the moments in each point of the girder are always positive, and the alternate positive and negative strains will be reduced to positive or tension or compression strains only. Thus, if I provide a separate strut or chord running from the abutment to the top and taking up the complete horizontal thrust of the bow, and constructed and calculated in the manner above described, the chords of my new girder will be entirely independent of the action of the thrust, and the moments acting upon them will always be positive—that is, the strains will at all times be tension and compression—and a plain tension eye-bar chord can be used in the new girder. This involves the arrangement of the struts so that they shall form at the crown an angle, each strut shaped according to the form found by the above-mentioned calculation. Moreover, in the new girder the chords are entirely independent of the height of the crown of the bow above the abutments for one and the same kind of loading.

My invention relates only to the chords of bow-girders, and is entirely independent of the system of bracing or construction of the bracing, which may be of any desired kind.

In illustration, I have shown in Figs. 1, 2, and 3 my new girder comprising in each half a plain compression upper chord, *b*, a plain tension lower chord, *a*, and suitable bracing. *A'* is a special strut extending from the crown-joint to the abutment, and the chords *a* *b*, with their bracing, are mounted thereon and connected thereto, so that the horizontal thrust of the girder is taken up wholly by the special strut *A'*, and none is communicated to the chords.

In the drawings the strut is placed midway between the two chords. It is scarcely necessary to say that it can be introduced in various other ways; also that the strut can coincide with one of the chords.

In a suspension-bridge, which is a reversed bow-girder, the methods given above can also be applied for calculation.

The characteristic features of my girder are always that the moments in any part of the

girder are always positive, whatever may be the position of the load, and the absolute value of the moments is independent of the height of the crown-joint above the abutments for one 5 and the same kind of loading.

Having thus described my invention, what I claim as new, and desire to secure by Letters Patent, is—

1. The combination, in a bow-girder having 10 joints at the top and at the abutments, of a plain tension and a plain compression chord and a special strut in union with said chords, substantially as and for the purpose set forth.

2. In a bow-girder, the combination, with 15 an upper plain compression-chord and a lower plain tension-chord united to each other by suitable trussing, of struts jointed together at the crown and jointed to the abutments, said chords and bracing being connected to said 20 struts, as described, and suitable supports for

the roadway, substantially as herein shown and described, and for the purpose set forth.

3. In a bow-girder, the combination, with 25 the two sections forming the bow, of struts jointed together at the crown and forming an angle, which struts are jointed to the abutments, and of suitable supports for the roadway, substantially as herein shown and described, and for the purpose set forth.

4. In a bow-girder, the combination, with 30 the two sections forming the bow, of curved struts jointed together at the crown and forming a Gothic arch, which struts are jointed to the abutments, and of suitable supports for the roadway, substantially as herein shown 35 and described, and for the purpose set forth.

EMMERICH A. WERNER.
